UNITED STATES PATENT OFFICE

BENJAMIN B. DEITEL, OF BROOKLYN, NEW YORK

DUPLEX NOVELTY CASE

Application filed December 2, 1929. Serial No. 411,112.

My invention relates to containers arranged to have separate compartments for different articles and, more particularly, to duplex or combination vanity and cigarette cases.

An essential feature of the invention is the novel locking device. The container has an intermediate closure releasably locked thereto. The hinged cover or lid of the container is locked to this intermediate closure so firmly that the lock can only be released by exerting an appreciable pulling force on the lid. Ordinarily, such a firm lock between lid and the intermediate closure would cause this closure also to be pulled open when the lid is pulled open. It is one of the objects of the present invention to hold the intermediate closure securely locked to the container when the lid is being pulled open.

Other objects of the invention are: to simplify the construction of such duplex containers, to reduce the number of parts necessary for the successful operation of the device, and to combine its elements in such a manner as to secure both sturdiness and attractive appearance.

These and further objects of the invention will become apparent from the detailed description which follows.

In the drawings, Figure 1 is a perspective view of a combination vanity and cigarette case embodying my invention; Figure 2 is a plan view of the same device, with the lid open, to disclose the vanity compartment; Figure 3 is a similar view of the same device, but with the intermediate closure open, to show the cigarette compartment; Figure 4 is a cross section taken along the line 4—4 of Figure 1; Figure 5 is an enlarged detail of the locking device; Figure 6 is a perspective view of a modification of the case shown in Figure 1; and Figure 7 is a cross section taken along the line 7—7 of Figure 6.

Referring to the figures in detail, 1 is an open frame constituting the walls of the container, shown here in the form simulating a book, the walls 1 having a multiplicity of parallel ridges to simulate the edges of the leaves of a book, on the three visible sides, viz., the front and the two ends of the "book".

The top, 2, or what is referred to in the claims as the "lid", comprises a flat open frame 5, reinforced with a cover plate 7, the frame 5 having bezels 6 within which is held a mirror 22. The bottom, 3, also, is provided with a reinforcing plate, 3', and is secured to the walls 1 by means of tongues 3", cut from the metal of the bottom plate 3, and riveted to the walls 1 by small rivets 3''. A cover, preferably of leather, 8, extends over the lid, 2, bottom, 3, and the back wall portion of 1, to simulate the binding of a book. This construction follows, to some extent, the one disclosed in my prior Patents, Nos. 1,694,702, 1,715,820 and 1,715,821, the only change being in the addition of the bottom plate 3, necessitated by the feature of the ridges on the walls 1. In the former patents, the lower frame was stamped out with outwardly projecting flanges to form a basis for the book "hang-over" and the reinforcing plate 3' was sufficient to build up the bottom. It is not, however, practical to make the ridges on the walls of such a frame. Accordingly, in the present case, the walls 1 are formed by merely bending a strip of sheet metal, the ends of which are held together on the back of the "book" frame, as by means of the joint 21, and are secured to the bottom, as explained above, by means of the tongues 3''. The strip of sheet metal thus used for the walls 1 is ridged before applied to the present construction. The cover 8 and the reinforcing plates 7 and 3' are secured to the open frame 5 and to the bottom 3, respectively, in the same manner as this has been shown in the above mentioned prior patents, namely, by means of channel members 9, for the top, and 9', for the bottom. The frame 5 is hinged to the back wall portion of 1 in the usual manner, as shown at 4. The bottom plate 3 is shown as hinged to the same wall at 4'. It should be understood, however, that this construction has been adopted merely as a matter of convenience. The hinge 4' has no function, the bottom being permanently secured to the walls 1.

A shallow tray 10, referred to in the claims as a "vanity tray", because of the rouge and powder puffs, 12 and 12', respectively,

separated by the holding bar 11, arranged in raised jointly with the lid to which it is locked, revealing the lower portion of the container which, in the illustration, is filled with cigarettes 23.

5 separated by the holding bar 11, arranged in raised jointly with the lid to which it is locked, revealing the lower portion of the container which, in the illustration, is filled with cigarettes 23.

10 It will be understood that the novel locking device of this duplex container has two distinct features, namely, (1) the lid 2 is locked to the container wall through the intermediary of the tray 10 and is operative, as between the lid 2 and the tray 10, when the lock between the tray 10 and the container wall 1 is released, and (2) the lock between the lid 2 and the container wall 1 (through the intermediary of the tray 10) is releasable only when the lock between the tray 10 and the container wall 1 is in operation.

15 The locking device herein shown also serves as a stop for the tray 10, the extension 14 of the tray abutting the lug 19 on its downward motion. In the drawing, a certain clearance is shown between the tray extension 14 and the lug 19, which is desirable to facilitate the release of the engaging hooks 14' and 14'', but the extension 14 actually does abut the lug 19 when the tray is closed down, slightly rebounding into the position shown in the drawing after first touching the lug.

20 It will be clear from the above description of my invention that it is not dependent upon the specific construction of the container as shown. The specific construction illustrated has been selected because it is preferred. To show that the choice is not limited, even were one to insist on a book form container, I have disclosed a modification in Figures 6 and 7, wherein the covering 8, of leather or other suitable material, is stretched over the top, bottom and back wall of the "book" form case, tucked over its edges in between the frame 5 and cover plate 7, on top, and between the bottom plate 3 and cover plate 3', at the bottom. The remainder of the duplex case structure is the same as before. Clearly, also, the container need not be of book form at all and may be of any shape or configuration. Such, and many other modifications, may be readily made by those skilled in the art without affecting the scope and the spirit of the invention.

25 I claim:

In order to release the lock between the container wall 1 and the tray 10, a lug 19 is attached to the movable portion 15'' of the leaf 15, as by means of the head 20, and is passed through an opening in the front portion of the wall 1, the projecting end of the lug 19 functioning as a thumb piece. The release is effected by simply pressing the lug 19 inward. This, however, will not in itself raise the tray 10. The tray is flush with the upper edge of the container wall 1 and presents no means for getting hold of the tray to raise it, unless by inserting a knife blade or other flat tool between the edges of the tray and of the container. In practice, the tray 10 is raised by closing the container, releasing the lock between the tray 10 and the container wall 1, i. e. pressing the lug 19 inward, and then raising the lid 2. There now being nothing to hold the tray down, it will be

ing said tray securely locked to said container wall when said lid is being pulled open.

3. In a container formed with a wall, a bottom, and a lid hinged to said wall, the combination with a tray mounted in said container to swing from said wall and adapted to form an intermediate closure for said container, of a spring lock between said lid and said tray releasable by exerting pull on said lid, means for releasably locking said tray when it is forming said intermediate closure, and means for securely holding said intermediary closure locked when said lid is being pulled open.

4. In a container comprising four sides, a bottom, and a lid hinged to the side forming the back wall of said container, the combination with a tray hinged to said back wall, of means selectively operative to releasably secure said lid and said tray as a unit to the side of said container forming its front wall, or to secure said tray to said front wall and release said lid from said tray.

5. In a container comprising four sides, a bottom, a lid, and a hinge between said lid and the side forming the back wall of said container, the combination with a tray mounted in said container to swing on said hinge, of a lock between said lid and said tray at the front end thereof, which lock is releasable by exerting pull on said lid, and means for holding said tray securely locked to the side of said container forming its front wall when said lid is being pulled open.

6. In a container formed with a wall, a bottom, and a lid hinged to said wall, the combination with a tray mounted in said container to swing from said wall and adapted to form an intermediate closure for said container, of a lock between said lid and said tray releasable by exerting pull on said lid, a hook on said tray, a cooperating hook on said wall adapted for engagement with the hook on said tray when the latter is forming said intermediate closure, and means for releasing said engagement.

7. In a container formed with a wall, a bottom, and a lid hinged to said wall, the combination with a tray mounted in said container to swing from said wall and adapted to form an intermediate closure for said container, of a spring lock between said lid and said tray releasable by exerting pull on said lid, an extension on said tray formed into a hook, a cooperating hook movably secured to said container wall and adapted to engage the hook on said tray extension when said tray is forming said intermediate closure, and means for actuating said movable hook to release it from engagement with the hook on said tray extension.

8. In a container comprising four sides, a bottom, and a lid hinged to the side forming the back wall of said container, the combination with a tray hinged to said back wall, of

a spring lock between said lid and said tray at the front end thereof releasable by exerting pull on said lid, an extension on said tray formed into a hook, a spring leaf secured to the side of said container forming its front wall, a hook on said spring leaf adapted for engagement with the hook on said tray extension, and means for actuating said spring leaf to release said engagement.

9. In a container comprising four sides, a bottom, and a lid hinged to the side forming the back wall of said container, the combination with a tray hinged to said back wall and adapted to form an intermediate closure for said container, of a spring lock between said lid and said tray, releasable by exerting pull on said lid, a downwardly projecting extension on the front end of said tray formed into a hook, a spring leaf secured to the side of said container forming its front wall, a hook on said spring leaf adapted for engagement with the hook on said tray extension when said tray is in the position forming said intermediate closure, and a lug attached to said spring leaf and outwardly projecting through said front wall.

10. A duplex vanity case comprising four sides, a bottom, a lid, a hinge between said lid and the side forming the back wall of said case, a vanity tray mounted in said case to swing on said hinge and adapted to form an intermediate closure for said case sufficiently spaced from said bottom to constitute, with the four sides of the said case, a separate container, a spring lock between said lid and the front end of said tray releasable by exerting pull on said lid, a downwardly projecting extension on the front end of said tray formed into a hook, a split spring leaf one portion whereof is secured to the side of said case forming its front wall, a hook on the other portion of said spring leaf adapted for engagement with the hook on said tray extension when said tray is in the position forming said intermediate closure, and a lug attached to the hooked portion of said spring leaf and projecting outwardly through said front wall, said lug being so disposed relatively to said tray extension as to constitute a downward stop for said tray.

11. A book form container comprising four walls, of which the front and the two end walls are provided with a multiplicity of parallel ridges to simulate the edges of the leaves of a book, a bottom, a lid, a hinge between said lid and the back wall of said container, a cover extending over said lid and bottom, and over said back wall, to simulate the binding of a book, a tray mounted in said container to swing on said hinge, a spring lock between said lid and said tray at the front end thereof, releasable by exerting pull on said lid, means for releasably locking said tray to the front wall of said container, and

means for holding said tray securely locked when said lid is being pulled open.

12. A book form duplex vanity case comprising four walls, the front and the two end walls being provided with a multiplicity of parallel ridges to simulate the edges of the leaves of a book, a bottom, and a lid hinged to the back wall of said vanity case, a covering extending over said bottom, lid and back wall, simulating the binding of a book, a tray mounted in said case to swing from said back wall, and means selectively operative to releasably secure said lid and said tray as a unit to said front wall, or to secure said tray to said front wall and release said lid from said tray.

13. A book form duplex vanity case comprising four walls, of which the front and the two end walls are provided with a multiplicity of parallel ridges to simulate the edges of the leaves of a book, a bottom, a lid, a hinge between said lid and the back wall of said case, a covering extending over said bottom, lid and back wall to simulate the binding of a book, a vanity tray mounted in said case to swing on said hinge, a spring lock between said lid and said vanity tray at the front end thereof releasable by exerting pull on said lid, said tray being adapted to form an intermediate closure for said case sufficiently spaced from said bottom to constitute, together with the four walls of said case, a separate container, a downwardly projecting extension on the front end of said tray formed into a hook, a spring leaf secured to the front wall of said case, a hook on said spring leaf adapted for engagement with the hook on said tray extension when said tray forms said intermediate closure, and a lug attached to said spring leaf and outwardly projecting through an opening in said front wall, said tray extension abutting said lug when said intermediate closure is effected.

14. A book form duplex vanity case comprising four walls, the front and the two end walls being provided with a multiplicity of parallel ridges to simulate the edges of the leaves of a book, a flat open frame hinged to the back wall of said case, a cover plate on said open frame, bezels on said frame to hold a mirror against said cover plate, a bottom secured to said four walls and extending beyond them on the front and on the two ends, a cover plate under said bottom, a covering extending over said top and bottom cover plates and over said back wall simulating the binding of a book, top and bottom channel members clasping together, one, the edges of said covering, top cover plate and flat open frame, and the other, the edges of said covering and of said bottom cover plate, along said front and end walls, a vanity tray hinged to said back wall, and means selectively operative to releasably secure said flat open frame and said tray as a unit to said front wall, or to

secure said tray to said front wall and release said flat open frame from said tray.

In testimony whereof I have affixed my signature.

BENJAMIN B. DEITEL.
